DITHIOCARBAMATE TUMOR-INHIBITORY
PROCESS

Koppaka V. Rao, Pine Brook, N.J., assignor to Chas. Pfizer & Co., Inc., New York, N.Y., a corporation of Delaware
No Drawing. Filed July 1, 1959, Ser. No. 824,170
6 Claims. (Cl. 167—78)

This invention relates to a method for inhibiting the growth of tumors and to a composition useful in such treatment. More specifically, it relates to a method for inhibiting malignant tumor growth in animals, including man.

Although the field of cancer therapy has been the subject of intensive study, particularly in recent years, so far extremely few effective substances have been found. Any extension of the range of available agents therefore represents a significant contribution to the knowledge of this important subject.

It has now been discovered that a class of compounds previously believed to be inactive actually possesses substantial tumor inhibitory activity. These valuable agents are the physiologically tolerable salts and esters of *N,N*-disubstituted dithiocarbamic acid. More specifically they are dithiocarbamates of the general formula

or

where M_1 may be an alkali metal ion, a radical derived from a pharmaceutically acceptable organic nitrogen-containing base by addition of a proton, or it may be alkyl, aryl or aralkyl; M_2 may be a pharmaceutically acceptable alkaline earth metal ion; and R_1 and R_2 when taken separately may be alkyl, aryl or aralkyl or taken together with the nitrogen to which they are attached, may form a heterocyclic ring.

M_1 may, for example, be sodium, potassium, lithium, mono-, di- or trialkylammonium in which the alkyl groups contain up to 12 carbon atoms; mono-, di- or trialkanolammonium in which the alkanol groups contain from 2 to 4 carbon atoms; it may be piperidinium, pyrrolidinium, morpholinium, pyrrolinium or *N*-alkyl derivatives thereof in which the alkyl group contains up to 3 carbon atoms; or it may be alkyl containing from 1 to 18 carbon atoms, phenyl or phenyl alkyl in which the alkyl group contains up to 4 carbon atoms; M_2 may be calcium or magnesium; and R_1 and R_2 may be alkyl containing from 1 to 18 carbon atoms, hydroxyalkyl containing from 2 to 4 carbon atoms, phenyl, phenylalkyl in which the alkyl group contains up to 4 carbon atoms, or taken together with the nitrogen atom to which they are attached R_1 and R_2 may represent 1-piperidyl, 1-pyrrolidyl, 1-morpholinyl, or 1-pyrrol groups or the like.

Some of these compounds are available commercially, while others are readily prepared by methods well known to those skilled in the art. For example, they may be prepared by reaction of a secondary amine with carbon disulfide. Where two moles of the organic base are employed the corresponding amine salt is recovered as a precipitated product. Such reactions are conveniently conducted in ether, and it is generally desirable to cool the reaction mixture. If an inorganic salt is desired, an equimolar combination of the corresponding inorganic base, the secondary amine, and carbon disulfide will generally be suc-

2

cessful. For such reactions aqueous media will be preferred. The esters and other amine salts are also readily prepared by standard methods.

The successful tumor-inhibitory activity herein reported was obtained in spite of prior teaching to the contrary, which might have been expected to discourage further study. Thus, it has been reported (Cancer Research, Supplement I, 1953, page 107) that the benzyl ester of diethyl dithiocarbamate failed to demonstrate activity in standard cancer screening tests.

It has now been discovered, however, that such substances are actually surprisingly effective in inhibiting the growth of malignant tumors.

The activity of these compounds is particularly pronounced against human carcinoma cells (strain He La) grown in tissue culture according to the procedure described by Rightsel et al. (Journal of Immunology, vol. 76, pages 467-74, 1956). In this test the described compounds are lethal to cancer cells at very low concentrations. For example, the sodium salt of diethylthiocarbamic acid completely destroys all cancer cells at concentrations as low as 0.5-2.0 mcg. per ml., and the diethylammonium salt is lethal at 0.2-2.0 mcg. per ml. Similarly, the piperidine salt of 1-piperidinocarbodithioic acid and the pyrrolidine salt of 1-pyrrolidinocarbodithioic acid are both lethal at a concentration of 3 mcg. per ml.

The compounds of the present invention exhibit significant anti-tumor activity against Crocker Sarcoma 180 in mice. According to the procedure described by Reilly et al. (Cancer Research, vol. 13, No. 9, pages 684-7, September 1953) the substance under test is dissolved in sterile 0.85% aqueous saline. Small, uniformly cut pieces of seven-day old tumor S-180 are implanted subcutaneously in the axillary region of Swiss white mice weighing 18 to 22 g. Each animal receives one implant, and the animals are divided into groups of six each. Intraperitoneal administration of the solution under test in doses of 0.5 cc. twice daily is begun 24 hours after implantation of the tumor and continued for a total of 13 injections. One group from each donor tumor is maintained as a control and receives injections of 0.85% saline. On the 8th day after tumor implantation the surviving animals are weighed to provide a measure of the toxic effect of the drug. The animals are then sacrificed and the tumors are excised and weighed. The weights for each group are averaged and the averages for the treated animals are expressed as percentages of the averages for the control groups. In this test it is found that the compounds of the present invention retard tumor growth to a marked degree at tolerable dosage levels.

These compounds also exhibit significant activity against mammary adenocarcinoma CA-755 according to the procedure of Gellhorn et al. (Cancer Research, Supplement III, page 38, 1955) in which treated groups of ten animals each are employed together with untreated controls.

Dosage is 0.5 cc. daily in all cases. Therapy is initiated one day after transplantation of the tumor and is continued for 12 days. At the conclusion of the experiment the animals are weighed and sacrificed, and the tumors are excised and weighed. Here again, the compounds of the present invention significantly retard growth of the tumors at the tolerated dosages. Furthermore, even where the tumor is permitted to become established by delaying the initiation of treatment for 6 days, retardation of growth is achieved.

Treatment every second day, or even every third day, is likewise beneficial. In addition to intraperitoneal administration, treatment by the subcutaneous route is also effective.

Like many carcinostatic agents, the compounds of the present invention are somewhat toxic substances. However, therapeutic doses can be administered without sub-

stantial adverse effect. As a first approximation, the relative safety of such agents may be estimated by calculating the ratio of the maximum dose tolerated by the host to the minimum dose lethal to the cancer cells. Such an approximation, for example, may be made in the following manner:

A maximum dose, D_M , tolerated by mice may be defined as that dose, expressed in micrograms of agent per gram of body weight, which at least 5% of the animals survive when treated once daily by the intraperitoneal route for five successive days. Experience with a large number of therapeutic agents has indicated that man can usually tolerate about $\frac{1}{20}$ of this level, or $D_M/20$, without adverse effects. Since the body weight is approximately one-tenth blood, such a dosage, if the agent is concentrated in the bloodstream, would provide a tolerated blood level of 10 times $D_M/20$ or $D_M/2$ in man. This value may be compared with the minimum concentration, LD_{TC} , expressed in mcg. of the agent per ml. which is found to completely destroy all tumor cells in the tissue culture test. The ratio of these two values,

$$\frac{D_M/2}{LD_{TC}}$$

for most chemotherapeutic agents now available for cancer therapy ranges from a value of about 5 to a value of about 25. In the case of the well known carcinostatic agent, Actinomycin D, this ratio has been determined to have a value of about 2.

The maximum dose of sodium diethyldithiocarbamate tolerated by mice in the test described above is found to be about 1500 mcg./g., and the tissue culture studies previously described show that a level of 1 mcg./ml. completely destroys all tumor cells. Thus, the ratio $D_M/2$ to LD_{TC} for this compound has the remarkably high value of 750. Although the long term effect of the compounds of the present invention in humans will not be known for some time, their proven capability of inhibiting tumors in animals together with their relatively high therapeutic indices, calculated as discussed above, strongly indicates their value in the therapy of malignant tumors such as sarcomas, lymphomas and carcinomas in human beings.

While these compounds may be administered orally, treatment by the parenteral route will usually be preferred. The substances may be employed in aqueous solution or dissolved in physiological saline, but various pharmaceutical preparations can be advantageously compounded which contain the active substance along with liquid or solid diluents. Solid preparations for extemporaneous dilution may be formulated employing various buffering agents as well as local anesthetics and other medicinal agents such as antibiotics, hypnotics, analgesics, etc., and inorganic salts to afford desirable pharmacological properties to the composition.

Doses of the order of 100 to 2000 mg./kg. daily of the compounds of the present invention are highly effective in inhibiting tumors in animals, and in human patients doses in the range of at least about 1 to 100 mg./kg. will be desirable. Therefore, the concentration of the active ingredient in the carrier will usually be at least about 0.1%. Since these active substances are stable and widely compatible, they may be administered in solution or suspension in a variety of pharmacologically acceptable vehicles, including water, propylene glycol, diethyl carbonate, glycerol, or oils such as peanut oil or sesame oil.

In addition to the conventional intramuscular, subcutaneous, intravenous, and intraperitoneal administration routes, these compounds may also be employed in conjunction with perfusion procedures, wherein the tumor site is isolated from the main circulatory system for treatment. Their particular usefulness in this procedure is indicated by their especially high effectiveness against tumor cells in tissue culture.

In some cases, particularly at the higher dosage levels, it may be desirable to employ combinations of some of the compounds of this invention. For example, in order to avoid sodium imbalance, combinations of the sodium salt with the calcium or potassium salt or with the salt of an organic base may be advantageously utilized for cancer therapy. In addition, these active substances may be employed in combination with one or more other carcinostatic agents. For this purpose, compositions containing from 10 to 90% of the compounds of the present invention are useful. Known carcinostatic agents which may be employed in such combinations include the nitrogen mustard type carcinostats, 6-mercaptopurine, 8-azaguanine, urethane, 6-diazo-5-oxo-1-norleucine, azaserine, triethylenemelamine, mitomycin C, triethylenephosphoramide, 1,4-dimethylsulfonyloxybutane, the carcinostatic folic acid analogs, ethyl carbamate, and the like.

The following examples are provided by way of illustration, and are not intended to limit this invention, the scope of which is indicated by the appended claims.

EXAMPLE I

Sodium diethyldithiocarbamate is tested for effectiveness in inhibiting the growth of adenocarcinoma CA-755 according to the procedure of Gellhorn et al. (loc. cit.). Administration is by the intraperitoneal route in each case. Results obtained are given in Table 1.

Table 1

Dosage mg./kg.	Body Wt. Change, g. treated/control	Survival Rate, treated animals	Tumor Wt. treated/control, percent
1,000	-1/+2	9/10	20
750	+1/+3	10/10	29
500	+1/+1	10/10	54

EXAMPLE II

The experiment of Example I is repeated, with various modifications, to determine the effect of less frequent tumor therapy, the effect of permitting the tumor to become established for 6 days before treatment is instituted, and the effect of subcutaneous administration, with results as given in Table 2. Dosage level is 1000 mg./kg. in each case.

Table 2

Modification	Body Wt. Change, g. treated/control	Survival Rate, treated animals	Tumor Wt. treated/control, percent
Treatment every other day	-1/+3	10/10	24
Treatment every third day	-1/+3	10/10	42
Established tumor	+1/+3	10/10	34
Subcutaneous	-1/+3	7/10	13

EXAMPLE III

Sodium diethyldithiocarbamate is evaluated for its effectiveness in inhibiting the growth of Sarcoma 180 following the procedure of Reilly et al. (loc. cit.). Results are as given in Table 3.

Table 3

Dosage mg./kg.	Body Wt. Change, g. treated/control	Survival Rate, treated animals	Tumor Wt. treated/control, percent
1,500	-1/-3	5/6	58
1,000	0/-3	6/6	67

EXAMPLE IV

The diethylammonium salt of diethyldithiocarbamate is evaluated for effectiveness against adenocarcinoma

CA-755 according to the procedure of Example I. At a dosage level of 500 mg./kg. average tumor weight in the treated animals is 67% of average tumor weight in the controls. 70% of the treated animals survive, with no change in body weight, while the controls show an average weight gain of 2 grams.

EXAMPLE V

The following substances are tested for their ability to retard the growth of malignant tumors according to the procedures of Examples I and III, and are found to be effective.

Piperidinium 1-piperidinecarbodithioate
 Pyrrolidinium 1-pyrrolidinecarbodithioate
 Morpholinium 1-morpholincarbodithioate
 Pyrrolinium 1-pyrrolecarbodithioate
 N-ethylpyrrolinium N',N'-diethyldihiocarbamate
 Calcium N,N-diethyldihiocarbamate
 Magnesium N,N-dimethyldihiocarbamate
 Potassium N,N-distearyldihiocarbamate
 Lithium N,N-diphenyldihiocarbamate
 Methyl N,N-di(2-phenyl ethyl)dithiocarbamate
 Stearyl N-methyl N-ethyl dithiocarbamate
 Phenyl N,N-diethyldihiocarbamate
 Benzyl N,N-diethyldihiocarbamate
 4-phenyl butyl N,N-diocetylthiocarbamate
 N-dodecylammonium N',N'-diethyldihiocarbamate
 N,N-dibutylammonium N',N'-dibutylthiocarbamate
 N,N,N-trimethylammonium N',N'-dibenzylthiocarbamate
 N-ethanolammonium N'-methyl N'-phenyl dithiocarbamate
 N,N-diethanolammonium N',N'-di(2-hydroxyethyl)dithiocarbamate
 N,N,N-triethanolammonium N',N'-diethyldihiocarbamate

EXAMPLE VI

A 0.1% solution of sodium diethyldihiocarbamate is aseptically prepared using isotonic saline as the vehicle. This solution is satisfactory for parenteral use in the treatment of tumors.

What is claimed is:

1. A process for retarding the growth of malignant tumors which comprises administering to a malignant tumor bearing host a daily dosage of from about 1 to 2000 mg. per kilogram of body weight of a substance represented by a formula selected from the group consisting of

and

wherein M₁ is selected from the group consisting of sodium, potassium, lithium, alkyl containing from 1 to 18 carbon atoms, phenyl, phenyl alkyl wherein the alkyl group contains from 1 to 4 carbon atoms; monoalkylammonium, dialkylammonium and trialkylammonium wherein the alkyl groups contain from 1 to 12 carbon atoms; alkanolammonium, dialkanolammonium, and tri-alkanolammonium wherein the alkanol groups contain from 2 to 4 carbon atoms; piperidinium, pyrrolidinium, morpholinium and pyrrolinium, and N-alkyl derivatives thereof wherein the alkyl group contains from 1 to 3 carbon atoms;

- M₂ is selected from the group consisting of calcium and magnesium;
- 15 R₁ and R₂ when taken separately are selected from the group consisting of alkyl containing from 1 to 18 carbon atoms, hydroxyalkyl containing from 2 to 4 carbon atoms, phenyl, and phenyl alkyl wherein the alkyl group contains from 1 to 4 carbon atoms;
- 20 R₁ and R₂ when taken together with the nitrogen atom to which they are attached are selected from the group consisting of 1-piperidyl, 1-pyrrolidyl, 1-morpholinyl and 1-pyrrolyl.
- 25 2. A process according to claim 1 wherein said substance is sodium diethyldihiocarbamate.
3. A process according to claim 1 wherein said substance is the diethylammonium salt of diethyldihiocarbamic acid.
- 30 4. A process according to claim 1 wherein said substance is the pyrrolidinium salt of 1-pyrrolidinecarbodithioic acid.
5. A process according to claim 1 wherein said substance is the piperidinium salt of 1-piperidinecarbodithioic acid.
- 35 6. A process according to claim 1 wherein said substance is the morpholinium salt of 1-morpholincarbodithioic acid.
